UNITED STATES PATENT OFFICE.

WILLIAM A. J. LOWE, OF BRISTOL, TENNESSEE, ASSIGNOR OF ONE-HALF TO GEORGE W. OVERSTREET, OF BRISTOL, TENNESSEE.

LAUNDRY-CONTAINER.

1,217,031.

Specification of Letters Patent. Patented Feb. 20, 1917.

Application filed February 7, 1916. Serial No. 76,760.

To all whom it may concern:

Be it known that I, WILLIAM A. J. LOWE, a citizen of the United States, residing at Bristol, in the county of Sullivan and State 5 of Tennessee, have invented new and useful Improvements in Laundry-Containers, of which the following is a specification.

This invention relates to containers especially adapted to be used for holding laundry as for instance, collars, cuffs and the like, and it consists in the novel features 10 hereinafter described and claimed.

An object of the invention is to provide a container of the character indicated which 15 is of simple structural arrangement and which includes means for efficiently protecting the articles which are deposited therein. Also the container includes means for sealing the same and suitable advertising matter 20 may be applied to the body of the container.

In the accompanying drawing:—

Figure 1 is a perspective view of the container.

Fig. 2 is a vertical sectional view of the 25 same with parts broken off.

Fig. 3 is a top plan view of the same.

The container includes a bottom disk 1 preferably of card board or similar material to which is applied a cylindrical body 30 2 of relatively thin paper. Suitable advertising matter may be displayed upon the bottom disk and the body. A ring 3 of cardboard or other suitable material fits snugly in the lower portion of the body 2 and rests at its lower edge upon the upper surface of the bottom disk 1 and in the vicinity of the edge of the said disk. The ends of the said ring are disconnected from each other whereby the said ring may fit 35 snugly in the lower portion of the body as indicated. A strip of paper 4 is secured at one end to the outer surface of the body 2 and in the vicinity of the edge of the disk 1 and the said strip is provided at its inner 40 sides with an adhesive which may be dampened to cause the disk to adhere to any particular part of the container with which it may be brought in contact.

When the articles of laundry as for instance, collars, are placed in the ring 3 and 50 upon the upper surface of the bottom disk 1 the upper portion of the body 2 is folded down within the ring and in the space which is left at the center of the collars. The strip 4 is then carried transversely 55 across the ring and down and along the under surface of the bottom disk 1 and may be secured by dampening the adhesive to the body and the bottom disk.

Therefore, it will be seen that when the 60 strip is applied as above indicated the contents of the container are securely held in position and the device may be conveniently used for carrying the articles of laundry.

Having described the invention what is 65 claimed is:—

1. A container comprising a bottom disk of relatively rigid material, a body of relatively flimsy material secured to the edge portion of the disk and completely surrounding the same, an expansible ring fitting in the said body and resting loosely at its lower edge upon the edge portion of the said bottom disk and means mounted on the body for holding the ring in a contracted condition.

2. A container comprising a bottom disk of relatively rigid material, a body of relatively flimsy material secured to the edge portion of the disk and completely surrounding the same, an expansible ring fitting in the body and resting loosely at its lower edge upon the upper surface of the bottom disk, and a strip fixed at one end to the body and adapted to be passed transversely across the ring and transversely of the disk and secured at its free end to the fixed end.

In testimony whereof I affix my signature in presence of two witnesses.

WILLIAM A. J. LOWE.
